(57) **CLAIM**

The ornamental design for an ear sampler, as shown and described.

DESCRIPTION

FIG. 1 is a front elevation view of an ear sampler showing the new design;

FIG. 2 is a back elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a top, front, left perspective view thereof;

FIG. 8 is bottom, rear, right perspective view thereof; and, FIG. 9 is a top, front, left perspective view shown exploded in condition of use for clarity of disclosure.

The equal-length broken lines depict portions of the ear sampler that form no part of the claimed design.

1 Claim, 9 Drawing Sheets
